UNITED STATES PATENT OFFICE.

ARTHUR G. HICKS, OF SARGENTS, COLORADO.

AUTOMATIC PRESSURE-TANK.

1,236,386.

Specification of Letters Patent.

Patented Aug. 7, 1917.

Application filed September 18, 1913, Serial No. 790,421. Renewed July 9, 1917. Serial No. 179,574.

To all whom it may concern:

Be it known that I, ARTHUR G. HICKS, a citizen of the United States, and a resident of Sargents, in the county of Saguache and State of Colorado, have invented a new and Improved Automatic Pressure-Tank, of which the following is a full, clear, and exact description.

This invention relates to steam boilers and has particular reference to devices of this kind adapted particularly for household use, though as to the particular purpose or adaptation I do not wish to be unnecessarily limited.

Among the objects of the invention is to devise a boiler with specially arranged connections whereby steam pressure within the boiler may be utilized in a new way to suck or draw water from a well or other source of supply and deliver the same either to the boiler to replenish the supply thereof or to any other place for use.

A further object of the invention is to provide a household boiler adapted to deliver either hot or cold water from a well or cold water.

A still further object of the invention is to arrange the water supply for a bathroom or the like in such a way that water may be delivered to the bathtub either hot or cold or at any intermediate temperature.

The foregoing and other objects of the invention will be hereinafter more fully described and claimed and illustrated in the drawing forming a part of this specification in which the figure is a vertical section of a boiler equipped with my improvements, certain of the parts being shown in elevation.

From what has been stated above, it will be understood that the several parts of the device may be made of any suitable materials and the location thereof may be varied also to a certain extent with relation to one another without departing from the spirit of the invention hereinafter more fully set forth and specifically claimed.

At 10 I show what may be regarded as an ordinary form of domestic boiler suitably supported upon a stand or tripod 11. The numeral 12 indicates a heater such as a cooking stove or range provided with a heating coil or water back 13 having connections with the boiler. A pipe 14 leads from the bottom of the boiler into the water back and the pipe 15 leads from the up-

per portion of the water back through the top of the boiler. The several pipes will, of course, be connected with the several water chambers by means of suitably packed joints. The connections, however, at 16 with the top of the boiler includes a pipe 17 extending from the top of the boiler to a point adjacent the bottom thereof and having a detachable filling plug 18 for the initial filling of the boiler. The boiler also is preferably equipped with a steam gage 19 and a safety valve 20 each having its usual functions.

At 21 I employ a well known type of inspirator, the same, however, being particularly adapted or reconstructed for my present uses. This inspirator is connected to the end 14^a of the pipe 14 on the opposite side of the boiler from the heater. That portion of the pipe indicated as 14^a is also provided with a check valve 23 and a globe valve 22. The check valve is arranged to open toward the boiler and prevents steam from forcing water through the pipe toward the inspirator, and the globe valve is adapted to completely close the pipe 14 under certain conditions. A steam pipe 24 extends from the top or steam space of the boiler down to the inspirator and this pipe is fitted with a globe valve 25.

To the lower portion of the inspirator is connected a suction pipe 26 leading from a well W or other source of supply. A discharge or overflow pipe 27 is connected to another portion of the inspirator and is provided with a globe valve 28.

The inspirator is provided with two stop cocks 29 and 30 either of which may be open while the other is closed, or both may be partially open at the same time, according to the result desired or the conditions with which the operation is carried on.

Having thus briefly set forth the construction, its method of operation may be described as follows:

Water first being supplied to the boiler to a point substantially midway of the gage glass 31 through the filling pipe 17, the water back 13 will consequently be filled at 105 the same time. Upon starting the fire in the heater, the water therein will become heated, forming steam in the steam space of the boiler. When the pressure gage indicates sufficient pressure according to the 110 work to be accomplished, the globe valve 25 in the steam pipe 24 will be opened. If

cold water is desired to be delivered from the discharge pipe 27, the valves 28 and 30 will be opened. Steam, therefore, will be forced through the inspirator, passing from 5 the barrel 32 thereof through the neck 33 and directly through the valve 30. This steam will, of course, be delivered with the water, but being in a comparatively small quantity with respect to the water delivered, 10 the water will not be excessively heated. If, however, hot water is to be delivered from the delivery pipe 27, the valve 30 will be closed; and the valve 29 opened, which will cause the course of the steam to be from 15 the barrel 32 through the neck 34 and valve 29, the quantity of steam in this case being much greater in proportion to the amount of water, it would serve to heat the water passing through the inspirator. The water 20 delivered, therefore, will be hot. Again, if the supply of water in the boiler becomes low, the valve 28 will be closed; and the globe valve 23 will be opened, which will have the effect of causing the inspirator to 25 automatically replenish the supply of water which will pass through the tube section 14^a and be delivered into the boiler through a series of perforations 14' of the tube 14, the water in this case being also delivered into 30 the boiler 10 hot, with the valves of the inspirator arranged as just described.

By means of the construction and arrangement herein shown, water can be forced in any direction as well as being elevated, 35 and the temperature of the water may be varied at will according to the control of the relative amounts of steam and water caused to pass through the inspirator, or, in other words, according to the various positions of the valves 29 and 30. With this apparatus, hot and cold water may be elevated to a bathroom or for any other purpose for which hot or cold water may be needed. The device can also be used in connection with city water supply or in connection with any other body of water, thus eliminating the necessity for having a storage tank supplying fresh water.

Having thus described my invention, I 50 claim as new and desire to secure by Letters Patent:—

1. The combination with a water back of a stove, of a pipe having communication with the water back and having a portion 55 projecting outwardly from the water back,

a tank receiving the projecting portion of the pipe, a second pipe having communication with the water back at a point above the first pipe and having communication with the interior of the tank by a pendant pipe, 60 a steam pipe communicating with the upper part of the tank, a suction pipe, a discharge pipe, and a valve means communicating with the steam pipe, the discharge pipe and the lower part of the tank and the first named pipe and operable to establish communication between the steam pipe, the suction pipe, and the discharge pipe, or between the steam pipe, the tank, and the discharge pipe, whereby the pressure of the 70 steam stored in the tank will be utilized to impart flow to water drawn through the suction pipe or tank.

2. A water pressure system consisting of a tank adapted to contain hot water and 75 provide a steam chamber above the level of the hot water, a water heater, a pipe communicating with the water heater and having an outlet end disposed in the tank below the normal water level, a second pipe having communication with the water heater and with the tank below the tank outlet of the first pipe and forming a cold water connection between the tank and the water heater, a steam pipe communicating at one 80 end with the steam chamber, a suction device connected with the other end of the steam pipe, a pipe connected with the suction device and having an open end adapted to be inserted in a cold water supply, a pipe 85 communicating with the tank below the water level and having communication with the suction device, a discharge pipe for the suction device and independently operative valve means arranged on the suction device 90 and the pipes for inducing a flow of hot water from the tank through the suction device and discharge pipe when steam is admitted to said suction device, or for inducing a flow of cold water or other fluid through 95 the cold water supply pipe, the suction device and discharge pipe.

In testimony whereof I have signed my name to this specification in the presence of two subscribing witnesses:

ARTHUR G. HICKS.
